RAZOR WITH ADJUSTABLE BLADE

Samuel Koffler, Brooklyn, N. Y.

Application January 25, 1950, Serial No. 140,471

2 Claims. (Cl. 30—73)

1

I have invented an improvement in razors; especially razors of the so-called safety type, comprising a handle and a fixed blade mounted on a guard at one end, with a cover element over the blade.

An important object of the invention is to provide a razor of this kind with a blade that can be adjusted so that its cutting edges lie either close to the guard, or with a small space between the blade and the guard, as the owner may wish, so as to be able to shave to the best advantage.

A further object is to provide a razor of the kind mentioned which is simple in construction and easy to produce, and which is made up of parts that can be readily assembled or dismounted and securely held in any position of adjustment while the razor is needed, so that there is no risk of slipping or causing injury to the user.

On the drawings:

Figure 1 is a longitudinal section of the razor with the parts in one position of adjustment.

Figure 2 is a section of the end of the razor in a plane at right angles to the plane of section in Figure 1.

Figure 3 is a section similar to Figure 1, with a different adjustment.

Figure 4 is a section through the head of the razor on the same plane as in Figure 2, showing the adjustment of Figure 3; and

Figures 5, 6 and 7 are plan views of the cover plate, the guard and the razor blade, respectively.

The razor comprises a guard 1 and a cover plate 2 therefor. The razor blade 3 is clamped between the guard and plate, and these three assembled parts are mounted on a handle 4, having screw threads in one end to engage a threaded stud 5 on the under face of the cover plate 2 and passing through an aperture 6 in the guard 1. In the middle of the guard 1 is a depression or cavity 7 which is preferably widest at the middle where the aperture 6 is located, and tapers towards the ends of the guard 1. Adjacent the long transverse edges of the guard and parallel thereto are ribs 8 to seat the blade 3, plate 2 and the cutting edges of the blade projecting beyond these ribs.

When the handle is screwed tight upon the stud 5, the cover plate 2, which has the usual shape and is concave on its under face, presses upon the sides of the blade 3 beyond the ribs 8 and forces these edges towards the guard 1. These spacings of the edges of the blade 3 from the edges of the guard 1 should be different for different individuals using the razor to yield the best results when shaving; and to this end the

blade 3 is adjustably mounted between the plate 2 and guard 1, so that its cutting edges can be close to the guard or permitted to recede therefrom under diminished pressure of the cover plate 2.

To afford such adjustment the guard has a spiral spring 9 in the recess or cavity 7, with the central part of this spring coiled around the opening 6 and stud 8. The ends of the spring are passed through openings 10 near the extremities of the guard, and turned against the guard as indicated at 11. Hence the spring is securely held in place. The central coiled part of the spring consists of a few turns, but these are sufficient to assure the necessary pressure upon both the guard, blade and cover plate; such pressure always tending to move the blade and plate away from the guard.

The handle has a bore 12 extending through it from end to end to receive a rod 13 having a knob 14 on its outer extremity. Inside the handle the bore 12 and rod or stem 13 have screw threaded engagement as indicated at 15 over a small part of the length of these members. The bore 12 adjacent the outer end of the handle also has an enlarged shouldered portion 16 and the rod has a section adjacent the knob 14 which fits this portion. Between the section 17 and the threaded portions 15 the rod fits the bore 12, so that it is held steady therein. At its inner extremity the rod 13 abuts the stud 5.

The cover plate 2 has ribs 18 on its concave inner face at both sides of the stud 5, extending therefrom towards the ends of the plate, and at the outer ends of these ribs are projections 19. The razor blade 3 has the usual slot 20 in the middle. When the blade is between the guard and cover plate, the ribs 18 pass through the slot 20 into the cavity 7, and the projections 19 enter the apertures 10. If the user desires an adjustment of the blade such as is shown in Figure 1, the handle 4 is screwed upon the stud 5 as far as it will go and the rod 13 is at first retracted, so that its inner end is out of contact with the stud 5. The cover plate is thus drawn down against the blade and its edges bend the blade 3 over the ribs 8 so that its edges are close to the guard 1. The rod is then screwed in to make contact with the stud 5.

On the other hand, if an adjustment with the cutting edges of the blade 3 farther from the guard 1 is desired, such as is illustrated in Figure 3, the user first makes sure that the rod is withdrawn slightly and then rotates the handle 4 so that the stud does not project so far into the

bore 12. The turns of the spring 9 then expand and force the plate and blade and the guard apart. The pressure of the edges of the plate 2 on the blade 3 is thus eased, and the elasticity of the blade tends to make it become more nearly flat. This is, the blade is bent to a smaller extent over the ribs 8. Then, by turning the knob 14, the inner end of the rod is forced against the stud, and the parts are bound in position. The razor can always be used without danger of the parts slipping or turning because the handle 4 and stem 14 press tightly against the guard and stud 5, binding the plate 2 because of the threaded engagement of the plate and handle, and the plate and razor are further secured against turning or twisting because the ribs 13 and the projections 19 go through the slot 20 in the razor and the projections 19 stay in the apertures 10 of the guard.

The construction and operation are therefore quite simple. The parts can be produced at relatively little expense, and the razor easily assembled and dismantled. The adjustment can readily and quickly be made to suit any individual user.

The plate 2 has the usual ribs or projections 21 at the corners to engage recesses 22 at the corners of the blade 3, and the edges of the guard 1 are of course bent away from the razor blade as indicated at 23, and the guard has slots 24 adjacent these bent edges.

The construction described is presented by way of example only, and changes in details may be adopted without departure from the general plan which contains the essential characteristics of the improvement.

Having described my invention, what I believe to be new is:

1. A razor comprising a guard, a cover member for securing a blade on said guard, the cover member having a threaded stud and the guard an opening through which the stud projects, the guard having parallel ribs at its sides for engaging the blade adjacent its cutting edges, a handle having a threaded bore in one end re- 45

ceiving the stud and a rod in the handle, said rod having its inner end threaded and engaged in said bore to abut the stud and hold the cover member in adjusted position, the guard having a cavity between said ribs facing said member and said blade when the blade is in position, and a compressed spring in said cavity for exerting pressure on said blade and member and said guard.

2. A razor comprising a guard, a cover member for securing a blade on said guard, the cover member having a threaded stud and the guard an opening through which the stud projects, the guard having parallel ribs at its sides for engaging the blade adjacent its cutting edges, a handle having a threaded bore in one end receiving the stud and a rod in the handle, said rod having its inner end threaded and engaged in said bore to abut the stud and hold the cover member in adjusted position, the guard having a cavity between said ribs facing said member and said blade when the blade is in position, and a compressed spring in said cavity for exerting pressure on said blade and member and said guard, said spring having a coiled part surrounding said studs, and having its ends attached to the guard adjacent the ends thereof.

SAMUEL KOFFLER.
